UNITED STATES PATENT OFFICE.

ALBERT T. WEISS, OF ROCHESTER, NEW YORK, ASSIGNOR TO YAWMAN & ERBE MANUFACTURING COMPANY, OF ROCHESTER, NEW YORK, A CORPORATION OF NEW YORK.

FOLLOWER FOR FILING-RECEPTACLES.

1,116,184.

Specification of Letters Patent.

Patented Nov. 3, 1914.

Application filed December 18, 1913. Serial No. 807,493.

To all whom it may concern:

Be it known that I, ALBERT T. WEISS, of Rochester, in the county of Monroe and State of New York, have invented certain new and useful Improvements in Followers for Filing-Receptacles; and I do hereby declare the following to be a full, clear, and exact description of the same, reference being had to the accompanying drawings, forming a part of this specification, and to the reference-numerals marked thereon.

My present invention relates to furniture and more particularly to office filing devices of the type designed for the vertical system of filing letters and papers, and it has for its object to provide a simple, cheap and convenient follower or compressor for cabinet drawers or other filing receptacles, the improvements being directed more particularly toward the locking mechanism for the follower and toward features connected with the construction of the follower and receptacle from sheet metal, rather than from wood or other material.

To these and other ends the invention consists in certain improvements and combinations of parts, all as will be hereinafter more fully described, the novel features being pointed out in the claims at the end of the specification.

In the drawings: Figure 1 is a perspective view of a filing receptacle and follower constructed in accordance with and illustrating one embodiment of my invention, the parts being viewed from the rear; Fig. 2 is a fragmentary horizontal section taken substantially on the line 2—2 of Fig. 1, and Fig. 3 is a fragmentary elevation of a rear edge of the follower partly in section through its guide on the line 3—3 of Fig. 1.

Similar reference numerals throughout the several figures indicate the same parts.

The receptacle, in the present instance, is constituted by a drawer such as is used in office and library filing cabinets, the same comprising a front 1, relatively lower side walls 2 and a bottom 3, and, as before indicated, the parts thereof are preferably constructed of sheet metal. The tops of the side walls 2 are surmounted by plates 4 that are first bent outwardly over the edge to furnish a supporting shoulder as at 5, and thence proceeding upwardly at 6 and finally flanged inwardly at 7 and downwardly at 8, the inward turn 7 being preferably semi-

circular or rounded as shown. The downturned flange 8 provides the retaining flange or wall for a laterally opening channel or guideway 9 running along each side of the receptacle.

The follower or compressor preferably comprises a flat plate 10 having rearwardly turned top and bottom flanges 11 and 12 and similar side flanges 13 which give strength and rigidity to the plate and at the same time serve in other capacities. In the side flanges 13 vertical slots 14 are formed constituting guides for the vertical or transverse movement of a lock bar 15 disposed horizontally transversely of the receptacle and of the follower plate 10. The projecting ends of this bar overhang the side walls of the latter and particularly the inturned flanges 7 at their margins, which flanges are each provided with notches forming teeth 16 that the ends of the bar are adapted to engage with when the latter is in its lowered position.

Just below the lock bar 15, there are riveted or otherwise secured to the ends of the follower plate 10, angular guide plates 17 that support the latter and that extend through openings in the flanges 13 and terminate in forwardly turned shoes 18 occupying the channels or guideways 9. These shoes rest on the shoulders 5 and are held against upward movement by the downturned flanges 8.

The lock bar 15 is provided with an operating member in the form of a plate 19 rigidly connected thereto and having a slot 20 therein through which extends a headed guide pin 21 on the rear face of the follower 10 flat against which latter the operating plate is disposed. Its upper portion is bent rearwardly at 22 to clear the top flange 11 of the follower and thence upwardly at 23. A spring 24 connected, as shown, has a normal tendency to draw down the plate 19 and hold the lock bar 15 interlocked with the teeth 16, preventing movement of the follower in the receptacle. By inserting the fingers beneath the portion 22 of the operating plate, however, the bar may be raised against the tension of the spring 24 out of engagement with the teeth on the receptacle permitting relative movement to the position sought and it will be noticed that the natural releasing grip that would be taken by the operator is also suitable for

sliding the follower in its guides 9 without changing the position of the hand in the least.

The general operation and purposes of such devices are too well known to those familiar with the art to warrant specific description.

I claim as my invention:

1. The combination with a filing receptacle having side walls provided with guides and a transversely extending follower movable longitudinally of the receptacle in the guides, of a series of vertically projecting teeth on each side wall of the receptacle above the guides and a locking device on the follower adapted to coöperate with said teeth.

2. The combination with a filing receptacle having side walls provided with guides and a transversely extending follower movable longitudinally of the receptacle in the guides, of a series of vertically projecting teeth on each side wall of the receptacle above the guides, a transversely extending 25 horizontally disposed and vertically mov-

able lock bar on the follower having laterally projecting ends coöoperating with the respective series of teeth, and an operating member rigidly connected to the bar and extending above the top of the follower. 30

3. The combination with a filing receptacle having side walls provided with guides formed by flanging inwardly and downwardly the top edges of the said walls and with respective series of teeth formed by 35 notching said flanges downwardly from the top or inwardly turned portions thereof, of a follower movable longitudinally of the receptacle, a horizontally disposed and vertically movable lock bar on the follower having laterally projecting ends overhanging the walls of the drawer and coöoperating with the respective series of teeth and shoes on the follower coöperating with the respective guides and offset from the ends of 40 the locking bar.

ALBERT T. WEISS.
